UNITED STATES PATENT OFFICE.

JOHN W. REYNOLDS, OF ERIN, TENNESSEE.

BALING-PRESS.

No. 809,844.

Specification of Letters Patent.

Patented Jan. 9, 1906.

Application filed August 24, 1905. Serial No. 276,592.

To all whom it may concern:

Be it known that I, JOHN W. REYNOLDS, residing at Erin, in the county of Houston and State of Tennessee, have invented certain new and useful Improvements in Baling-Presses, of which the following is a specification.

This invention relates to certain new and useful improvements in baling-presses; and it particularly relates to that class of presses known as "hay and straw baling-presses," although I desire it understood that it can be used in connection with any reciprocating plunger-presses either for baling hay, straw, cotton, or other material.

In its generic nature my invention comprises a double-cam driving mechanism for reciprocating the plunger to compress the material, which driving mechanism is so arranged that the leverage exerted on the reciprocating plunger is increased as the pressure against the piston increases, so as to compensate therefor.

In its more detailed nature the invention comprises a drive mechanism consisting of an S-shaped double cam, means for turning said cam, means co-operatively connecting said cam with a reciprocating plunger, means for always holding the plunger in engagement with a cam, and means carried by the cam for releasing the plunger during every half-revolution.

Primarily my invention has for its object to provide a device of the character stated of a very simple and effective construction which can be easily and cheaply manufactured and which can be attached to any reciprocating plunger-press and will readily and effectively serve its intended purposes.

With other objects in view than have been heretofore enumerated the invention also comprises certain novel construction, combination, and arrangement of parts, all of which will be first described in detail and then be specifically pointed out in the appended claims, reference being had to the accompanying drawings, in which—

Figure 1 is a perspective view of my invention as applied for use. Fig. 2 is a top plan view thereof. Fig. 3 is a vertical longitudinal section of my invention, showing the position of the parts just after the plunger has been released from the cam. Fig. 4 is a horizontal section on the line 4-4 of Fig. 3 looking in the direction of the arrow. Fig. 5 is a detail perspective view of the cam-engaging

end of the plunger. Fig. 6 is a detail perspective view of the cam member.

Referring now to the accompanying drawings, in which like numerals of reference indicate like parts in all of the figures, 1 designates the baling-chamber, in which the piston 2 is reciprocally mounted, all of which may be of any approved construction, as the same *per se* forms no part of my present invention. The piston 2 has the usual plunger-arm 3, as shown.

4 designates a beam connecting the baling-chamber frame with a base 5, upon which a frame 6 is mounted, and the frame 6 includes a pair of parallel bearing-arms 7 7, spaced 70 apart and provided with bearing portions 7^a 7^b, as shown, the lower arm 7 being spaced above the beam 4 for a purpose presently explained.

8 designates a shaft mounted in the bearing 7^a 7^b of the arms 7 7, which shaft carries a double or S cam 9 at its lower end and a sweep-lever 10 at its upper end, to which the swingletree 11 is attached to enable the shaft 8 to be turned by horse-power. The cam 9 is substantially an S-shaped cam and comprises the double-cam portions 9^a 9^b, respectively, which are separated at their adjoining ends to leave a passage 9^b of sufficient width to permit passage of the piston-rod 3. The piston-rod 3 has a friction-roller 3^a at its free end for engaging with the cam portions 9^a 9^b, as shown.

13 designates a cross member secured to the beam 4, having an abutment 13^a to prevent the piston-rod 3 from moving laterally in one direction, and the piston-rod is normally held against the abutment 13^a by a spring-arm 14, carrying a friction-roller 14^a, which engages the piston-rod 3, as shown.

15 designates a spring member secured to the abutment 13^a and to the piston-rod 3 to normally move the piston in the direction of the arrow.

So far as described, the manner in which my invention operates will be best explained as follows: Motion is imparted to the sweep 10 in the direction of the arrow, which causes the outer end of the cam-section 9^a to engage the friction-roller 3^a and move the piston in a direction opposite to the indicating-arrow. As the sweep-arm moves in the direction indicated the piston 2 will be forced in to compress the bale, and as the bale is becoming compressed it takes more power to compress the same toward the finish of the stroke of the piston than at the beginning thereof, and

this is compensated for by the arrangement of the cam-sections 9^a 9^a, which move the piston-rod, with its roller 3^a, toward the axial line of the shaft 8 as the piston 2 is moved inward 5 to compress the bale, thus giving increased leverage as the bale becomes compressed. When the friction-roller 3^a has rolled around one cam-section 9^a and reaches a position in alignment with the shaft 8, the same will 10 come in alignment with the passage 9^b and be released from the cam by the spring 15, which moves the piston-rod 3 in the direction of the arrow to the limit of its movement in such direction, when it is ready to become engaged 15 by the second section 9^a in the cam member 9 and move back to compress the material again.

16 designates any suitable buffer for receiving the impact of the piston-rod 3 as it is released from engagement with the cam 9.

By making the plunger 3 laterally movable and by providing the spring 14 and roller 14^a as shown in the operation of my invention the lateral strains on the plunger 3 25 are counterbalanced, and, furthermore, by reason of such arrangement of parts and by reason of the S-shaped cam the leverage is varied properly so that the strain on the horse is maintained nearly even during the 30 entire travel of the sweep-arm 10 around its fulcrum, whereas should the plunger 3 be not laterally movable, but merely longitudinally reciprocable, there would be considerable lateral strain on the plunger, and the greatest 35 power would have to be applied during the beginning of the stroke of the plunger from the position shown in Fig. 4, and it would take more power to start the plunger from left to right in Fig. 4 were it not laterally 40 movable than it takes when the plunger is laterally movable, as shown, since the lateral strain in starting the plunger is practically eliminated by the arrangement shown in the drawings.

45 From the foregoing description, taken in connection with the accompanying drawings, it is thought the complete construction, operation, and many advantages of my invention will be readily understood by those 50 skilled in the art to which it appertains, and I desire to say that many slight changes in the detailed construction, operation, and arrangement of parts may be made without departing from the scope of the invention or the 55 appended claims.

Having thus described my invention, what I claim, and desire to secure by Letters Patent, is—

1. An apparatus of the class described, 60 comprising in combination with a baling-press having a laterally-movable reciprocating plunger, of an S-shaped cam for co-operating with said plunger to reciprocate the same, and means for releasing said plunger from 65 said cam at times.

2. An apparatus of the class described, comprising the combination with a baling-press having a laterally-movable reciprocating plunger, of a double-cam member, means for rotating said cam member, said plunger 70 and cam being co-operatively arranged, means for releasing said plunger from said cam member at times, substantially as shown and described.

3. An apparatus of the class described, 75 comprising in combination with a press having a laterally-movable reciprocating plunger, of a shaft mounted in a plane at right angles to the plane of reciprocation of the plunger, a double-cam member secured to 80 said shaft, means for rotating said shaft, said cam member and said plunger being co-operatively connected, means for holding said plunger in engagement with said cam, and means for releasing said plunger from said cam at 85 times, substantially as shown and described.

4. An apparatus of the class described, comprising the combination with a laterally-movable reciprocating member, of a power mechanism for reciprocating said member 90 and comprising an S-shaped cam member having double-cam portions, said double-cam portions being separated at the center of the S-shaped member to leave a passage-way, means for rotating said cam member 95 and means for forcing the reciprocating member through said cam passage-way when in alignment therewith, substantially as shown and described.

5. An apparatus of the class described, 100 comprising the combination with a baling-press having a laterally-movable reciprocating plunger, an S-shaped cam member, means for rotating said S-shaped cam member to engage said reciprocating plunger to 105 reciprocate the same in one direction, spring devices for reciprocating the plunger in the opposite direction, said cam member having means for permitting the plunger to be disengaged therefrom at times, substantially as 110 shown and described.

6. An apparatus of the class described, the combination with a baling-press having a laterally-movable reciprocating plunger, an S-shaped cam member, means for rotating 115 said S-shaped cam member to engage said reciprocating plunger to reciprocate the same in one direction, spring devices for reciprocating the plunger in the opposite direction, said cam member having a passage midway 120 its ends to permit the plunger becoming released from the cam as it comes in alignment with said passage substantially as shown and described.

7. An apparatus of the class described, 125 comprising in combination with a press having a laterally-movable reciprocating plunger, of a cam member adapted to engage the end of said plunger to move it in one direction, a spring member secured to the plunger 130

to move it in the opposite direction, said cam member comprising an **S**-shaped member having a double-cam face and a central passage, means for holding the plunger in engagement with the cam-face and means for imparting rotary motion to the cam, substantially as shown and described.

8. An apparatus of the class described, comprising in combination with a baling-press having a laterally-movable reciprocating plunger, of a power mechanism therefor, said power mechanism comprising a drive-shaft vertically mounted in the central longitudinal plane of the press, an **S**-shaped cam member secured to said shaft, a sweep-arm secured to said shaft for rotating the same, said **S**-shaped cam member including a plurality of cam portions spaced apart to form a passage-way, a friction-roller on the end of said plunger for coöperating with the cam, means for holding the plunger with its friction-roller in engagement with the cam, means for releasing said plunger from said cam and forcing it through the passage-way thereof as the friction-roller comes in alignment therewith substantially as shown and described.

9. An apparatus of the class described, comprising in combination with a baling-chamber, and a plunger including a piston-rod and a piston-head longitudinally recipro-

cable with respect to said baling-press, of an **S**-shape cam for coöperating with said piston to reciprocate the same means for releasing said piston from said cam at times, said piston being laterally movable in a plane at right angles to the axis of the cam, means for normally holding said piston in a longitudinal plane with the axis of the cam and means for moving said piston in one direction when released from said cam substantially as shown and described.

10. An apparatus of the class described, the combination with a reciprocating member having lateral movement, of a power mechanism for reciprocating said member and comprising an **S**-shaped cam member having double-cam portions, said double-cam portions being separated at the center of the **S**-shaped cam member to leave a passage-way, means for rotating said cam member, means for forcing the reciprocating member through said cam passage-way when in alinement therewith, means for normally holding said reciprocating member in alinement with said cam passage-way, substantially as shown and described.
